Attorneys

UNITED STATES PATENT OFFICE.

HARRY WILLARD MILLER, OF ANN ARBOR, MICHIGAN.

BUTTON FASTENING.

Application filed September 10, 1924. Serial No. 736,881.

My invention relates to button fastenings, and particularly to that type wherein the use of thread is entirely eliminated in the application of a button to a desired fabric.

5 It is the purpose of my present invention to provide a button fastening of the type indicated which is adapted to be applied to a desired fabric without penetration or mutilation thereof; which is readily adapted for 10 application either through the medium of a manually operable tool or by suitable power operated machinery; which will permit universal motion of any associated button with respect to the fastening and the carrying 15 fabric of a garment, and thereby relieve the latter of considerable strain incident to buttoning and unbuttoning of such garment; which is simple in construction, efficient in use, and which can be manufactured at small 20 cost.

I will describe my invention in the best form known to me at present, but it will be apparent that the same is susceptible to changes in forms and proportions and to 25 desirable additions with the exercise of only ordinary mechanical skill and without departing from the scope thereof, as set forth in the appended claims.

In the drawings chosen to illustrate my 30 invention.

Figure 1, a view showing a button and the elements of my improved fastening separated with respect to each other, said button and elements each being shown in section;

35 Figure 2, a sectional view showing the outer clamping plate of my improved fastening and the dished button carrying disk in assembly;

40 Figure 3, a sectional view showing the button in assembly with the structure disclosed in Figure 2;

45 Figure 4, a sectional view showing one status in assembling the outer and inner clamping plates in clamping relation to a desired fabric and through the instrumentality of a suitable tool;

50 Figure 5, a sectional view showing complete assembly of the inner and outer clamping plates and the associated elements disclosed in Figure 4;

Figure 6, a sectional view showing a modified form of inner clamping plate;

55 Figures 7 and 8, views similar to Figures 4 and 5, respectively, with the modified inner clamping plate included; and

Figure 9, a fragmental perspective view

of the jaws of a plier tool adapted to be employed in the assembly of the parts as shown in Figures 4 and 7.

In the drawings, my improved fastening is shown as comprising an outer clamping plate A, an inner clamping plate B, and a dished button carrying disk C. The plate A, preferably, is circular and embodies a central hollow head 10 shown in its initial shape in Figure 1. In the assembly of the plate A and disk C the head 10 is passed through a central opening 10' in said disk, and then is expanded at its outer end by any suitable means to so engage the disk C on the head 10 as shown in Figure 2, as to provide a universal motion connection between the two parts in which assembly these elements are adapted to be commercialized.

The inner clamping plate B is also circular and preferably of the same diameter as plate A. This plate B has a tubular central head 12 provided at its outer end with an internal strengthening head 13, said head being of a diameter to permit its engagement within the head 10. To assemble the plate B with the previously assembled plate A and disk C so as to confine a desired fabric between said plates I employ a plier tool,

one desirable form of which is shown in Figure 9. Such tool comprises jaws 14 and 15, the former of which has its free end recessed as at 16, while the latter carries on its inner face a stud 18 positioned to enter recess 16 when the jaws are contracted. Ad-

90 jacent to recess 16 the outer face of jaw 14 is chambered as at 17 to correspond to the curvature of the disk C so that said jaw may be engaged between said disk and plate A. In effecting assembly of the plate B with the plate A as shown in Figures 4 and

5, the jaw 14 of the plier tool is positioned between the disk C and plate A with the head 10 engaged in the recess 16. Plate B then is placed over the inner face of plier

100 jaw 15 with the stud 18 projecting into the tubular central head 12. With this status existing the fabric, indicated at D, is suitably positioned between the plates A and B. The jaws 14 and 15 then are contracted

105 with the result that during the first portion of such contraction the fabric D will be forced into the head 10 in advance of the head 12 until it abuts the outer end of the head 10 when further contraction of said

110 jaws will cause the pin or stud 18 to expand the outer end of the head 12 and thus

interlock the plates A and B with the fabric D clamped therebetween, the portion of the fabric between the plates being continuous and unmutilated as will be obvious.

5 A button of the type adapted for association with the disk C is indicated at E, and is shown provided on its inner face with a groove 19, into which the outer edge of the disk C is inserted, while the disk is compressed so that when the disk thereafter is 10 permitted to expand the button will be firmly united therewith as is manifest.

15 In Figures 6, 7 and 8, I have shown a modified form of inner clamping plate which is distinguished from the inner clamping plate previously described, in that the head 12 is provided with an external head 20. By this construction the possibility of the head being crushed by the stud 18 during 20 assembly and application is eliminated. It will be observed in connection with this modified form of inner clamping plate that at the point where the external head 20 is provided, the internal diameter of the head 25 is reduced so that said head will lie substantially flush with the outer surface of the remainder of the head. By this arrangement the same amount of expansion of the head 12 to effect assembly is required in 30 the modified form as in the form previously described.

What I claim, is:—

1. A button fastening comprising a button carrying disk having an aperture, a clamping plate having a hollow head extending through said aperture and expanded at its free end, and a second clamping plate having a hollow head nested and expanded in the head of the first plate to interlock said plates with fabric clamped therebetween, the head of the second plate being open at its base end whereby said head may be expanded within the head of the first plate by an expanding tool inserted therein at the base end thereof. 35

2. A button fastening comprising a button carrying disk having an aperture, a clamping plate having a hollow head extending through said aperture and expanded at its free end, and a second clamping plate having a hollow head open at its base end and nested and expanded in the head of the first plate to interlock said plates with fabric clamped therebetween, the head of said second plate before connection with the first plate being of less internal diameter at its free end than at its base end whereby said head may be expanded within the head of the first plate by an expanding tool inserted therein at the base end thereof. 40 45 50 55

HARRY WILLARD MILLER.
